UNITED STATES PATENT OFFICE.

JOHN F. SNOW, OF BROCKTON, MASSACHUSETTS.

DESIGN FOR A FOUNTAIN-BRUSH.

SPECIFICATION forming part of Design No. 30,262, dated February 28, 1899.

Application filed January 23, 1899. Serial No. 703,181. Term of patent 7 years.

To all whom it may concern:

Be it known that I, JOHN F. SNOW, a citizen of the United States, residing at Brockton, in the county of Plymouth and State of Massachusetts, have invented and produced a new and original Design for Fountain-Brushes, of which the following is a specification.

Figure 1 is a perspective view of a fountain-brush, showing my design. Fig. 2 is a longitudinal sectional view of the same, taken on the line $x-x$ of Fig. 1.

As shown in the drawings, the leading or material feature of my design consists of a handle portion flattened horizontally at its forward end and having extending centrally from one side of its flattened portion a flat tube having forwardly-inclined front and rear walls, said tube carrying a spreader in the form of a block or pad having a straight edge or working surface and a rear wall made substantially dovetailed in shape.

The handle A is made hollow in the form of a reservoir, and its front portion is horizontally flattened at B, and rising from the upper surface of this flattened portion is a short nipple or tube C for a screw-cap D. From

the lower surface of the flattened portion of the handle extends a vertically-disposed flat tube E, which contains, and from the lower edge of which projects, a pad or block F, having a straight edge at α and a dovetailed rear edge, the upper portion of this pad or block being inclosed within the flat tube, which latter has forwardly-inclined front and rear walls, and also has an opening connecting it with the interior of the handle. The lower portion of the flat tube E is also contracted transversely and embraces the pad or block at a point between the ends of the latter, as shown.

Having described my invention, what I claim as new, and desire to secure by Letters Patent, is—

The design for a fountain-brush substantially as herein shown and described.

In testimony whereof I have hereunto set my hand in presence of two subscribing witnesses.

JOHN F. SNOW.
